UNITED STATES PATENT OFFICE

91,420

DESIGN FOR A SPINNING TOP AND HOLDER

Fabio Conti, Chicago, Ill.

Application October 28, 1933. Serial No. 49,589

Term of patent 3½ years

To all whom it may concern:

Be it known that I, FABIO CONTI, a citizen of the United States, residing at Chicago, in the county of Cook and State of Illinois, have invented a new, original, and ornamental Design for a Spinning Top and Holder, of which the following is a specification, reference being had to the accompanying drawing, forming part thereof.

Figure 1 is a view in front elevation of a spinning top and holder showing my new design.

I claim:

The ornamental design for a spinning top and holder as shown.

FABIO CONTI.
